UNITED STATES PATENT OFFICE

105,131

DESIGN FOR A KITCHEN AND BATHROOM HANGER

George Clifford Neth, Dayton, Ohio

Application April 7, 1937, Serial No. 68,588

Term of patent 14 years

To all whom it may concern:

Be it known that I, George Clifford Neth, a citizen of the United States, residing at Dayton, in the county of Montgomery and State of Ohio, have invented a new, original, and ornamental Design for a Kitchen and Bathroom Hanger, of which the following is a specification, reference being had to the accompanying drawing, forming part thereof.

The design is a combination of a Scotch terrier

dog with a large bow on its tail representing a ribbon and below the dog is a base or foundation on which the figure is standing.

The figure is a plan view of a kitchen and bathroom hanger, showing my new design.

I claim:

The ornamental design for a kitchen and bathroom hanger, as shown and described.
